UNITED STATES PATENT OFFICE.

EXILIAS PAQUETTE, OF LOWELL, MASSACHUSETTS, ASSIGNOR TO LAWRENCE MANUFACTURING COMPANY, OF LOWELL, MASSACHUSETTS, A CORPORATION OF MASSACHUSETTS.

CIRCULAR-KNITTING MACHINE.

1,092,166.

Specification of Letters Patent.

Patented Apr. 7, 1914.

Application filed November 25, 1911. Serial No. 662,265.

To all whom it may concern:

Be it known that I, EXILIAS PAQUETTE, a citizen of the United States, residing at Lowell, in the county of Middlesex and 5 State of Massachusetts, have invented certain new and useful Improvements in Circular-Knitting Machines; and I do hereby declare the following to be a full, clear, and exact description of the invention, such as will 10 enable others skilled in the art to which it appertains to make and use the same.

The invention relates to that class of circular knitting machines in which the needles are operated upon by cams and devices 15 arranged about the cylinder, the relative movements between the needles and needle operating devices requisite for knitting a tubular fabric provided at intervals with heel and toe pockets being produced by rotary 20 and reciprocatory movements of either the needle cylinder or the support or cylinder on which the needle operating devices are mounted.

The invention is intended primarily as an 25 improvement in the machine shown and described in the patents to Hemphill, No. 933,442, September 7, 1909, and No. 935,981, October 5, 1909, and known as the "Banner" machine. It will be understood, however, 30 that the invention is not limited in its application to this machine, and that certain features of the invention may be embodied in other constructions and other forms of circular knitting machines adapted for knitting 35 seamless hosiery.

In the Banner machine, as is usual in this 40 type of knitting machine, the change of the knitting motion from rotary to reciprocatory and back to rotary, and the throwing into and out of operation of the devices for raising or lowering the long butt or instep needles, and the throwing into and out of 45 operation of the devices for raising and lowering individual needles for narrowing and widening, are effected by controlling cams on a cam shaft which is fed forward or advanced at proper intervals and which makes one revolution during the knitting of each stocking. The controller cam shaft also 50 carries the cams for actuating the yarn guides to change the yarn at certain parts of the stocking. With this construction the points at which, and the frequency with 55 which the yarn may be changed, is limited, since the proper operation of the needle con-

troller cams requires the cam shaft to be advanced at certain definite intervals, and also requires that the movements given to the cam shaft shall be in the same sequence for each stocking.

It is the object of the present invention to provide an improved mechanism for actuating the yarn guides to change the yarn which will enable the yarn to be changed at any desired point or points in the knitting 65 of the stocking.

It is a further object to provide a mechanism of this character the operation of which may be varied to vary the point at which the yarn is changed without affecting 70 the operation of the controller cam shaft.

It is a further object of the invention to provide a mechanism of the above character which may be readily applied to the Banner machine, and to otherwise improve the yarn 75 changing mechanism of this machine.

To these ends the invention consists in the features of construction and combination of parts hereinafter described and referred to in the claims.

The various features of the invention will be readily understood from an inspection of the accompanying drawings and the following detailed description of the mechanisms illustrated therein.

In the drawings Figure 1 is a front elevation partly in section showing a Banner machine provided with the present improvements; Fig. 2 is a detail side elevation showing a part of the mechanism for operating 90 the yarn guides to change the yarn; Fig. 3 is a sectional plan view on line 3—3, Fig. 2; Fig. 4 is a plan view showing the yarn guiding and holding devices; Fig. 5 is a vertical sectional view on line 5—5, Fig. 4; Fig. 6 95 is a detail elevation showing the devices for controlling the operation of the yarn changing mechanism; and Fig. 7 is a detail sectional elevation showing a part of the yarn changing mechanism.

As shown in the drawings, the invention is embodied in the Banner machine hereinbefore referred to, and only so much of that machine has been illustrated as is necessary to understand the application of the present improvement thereto.

The needle cylinder 1, the plate 2 carrying the knitting cams, the cams for throwing the long butt or instep needles into and out of action, the narrowing and widening pickers, 110

and the devices for throwing them into and out of action, are all the same and are operated in the same manner as in the Banner machine fully described in the patent to 5 Hemphill, No. 933,443. The needle cylinder is driven through a bevel gear 3 which is secured to a driving shaft 4, and the knitting motion is changed by a motion-changing clutch 5 as in the banner machine.

10 The machine is provided with a controller cam shaft 6 which carries the cam 7 for changing the knitting motion, the speed changing cam 8, the fashioning cams 9 for varying the height of the plate 2, and the cam 15 10 for throwing the widening pickers into and out of operation, all of which are constructed and operated in the same manner as the corresponding devices in the Banner machine. The controller cam shaft 6 is intermittently advanced or fed forward during 20 the knitting of a stocking by a pawl 11 pivoted to the oscillating segment 12 of the cylinder reciprocating mechanism. The pawl 11 is arranged to engage teeth formed 25 on a ratchet wheel 13 secured to the cam shaft, and the pawl is held normally out of engagement with the teeth of the ratchet wheel by the rear end of a controller lever 14. The front end of the controller lever is 30 provided with a laterally projecting finger 15 arranged to be engaged by lugs 16 on a pattern chain 17 which is carried by a sprocket wheel loosely mounted on the cam shaft and connected with a ratchet wheel 18.

35 The pattern chain is fed forward during the operation of the machine by a pawl 19 connected with the oscillating segment 12 and arranged to engage the ratchet wheel and advance it a single tooth during each recip- 40 rocation of the segment. When one of the lugs 16 engages the finger 15 on the controller lever 14, the rear end of the lever is depressed so that the pawl 11 engages the teeth on the ratchet wheel 13 and advances 45 the controller cam shaft one or two steps, as the case may be. The construction and operation of this mechanism is that of the corresponding mechanism in the Banner machine. The yarns are led to the needles 50 through eyes formed in the front ends of the yarn guides 20, 21 and 22. For convenience in describing the mode of operation of the yarn changing devices, it will be assumed that a black yarn B is led through the eye at 55 the end of the yarn guide 21, a reinforce black yarn b is led through the eye at the end of the yarn guide 20, and that white yarn W, either a single yarn or a double yarn, is led through one of the eyes at the end of the 60 yarn guide 22. The yarn guides consists of levers pivoted at 23 to the latch ring 24 and acted upon by springs 25 which tend to hold them in depressed or active position against a supporting plate 26. The yarn guides are 65 raised against the tension of the springs 25

to withdraw the yarns carried thereby from the needles by levers 27 connected by cords 28 with levers 29, 30 and 31, which are arranged with their front ends overlying a drum 32 on the controller cam shaft. The lever 29 which actuates the yarn guide 20 carrying the reinforce yarn b is arranged to engage and be actuated by cam ribs 33 on the drum 32, the cam ribs being arranged to lift the front end of the lever 29 and thus 70 raise the yarn guide 20 and withdraw the reinforce yarn from the needles during the knitting of the leg and foot of the stocking. 75 As thus far described, the yarn changing guides and the devices through which they are operated are the same in construction and arrangement as the corresponding devices in the Banner machine. In the Banner machine the levers 30 and 31 are also actuated to change the yarn from black to white, 80 or white to black, by cam ribs secured to the drum 32, and these ribs are constructed to effect the changing of the yarn during the feed of the controller cam shaft at the beginning or end of the heel or toe. In embodying the present improvements in the Banner machine, means is provided for actuating the levers 30 and 31 independently of the controller cam shaft, so that the yarn guides 85 may be actuated to change the yarn from black to white, or white to black, at any time during the knitting of the stocking, and without disturbing the setting or timing of the controller cam shaft. In its preferred construction this means comprises a yarn 90 changing cam or series of cams and means for controlling the operation of the cam or cams from the pattern chain. As shown, the yarn changing cam comprises a series of cam plates 34 and 35 secured to the face 95 of a ratchet disk 36 and arranged to engage a pin 37 projecting laterally from a lever 38. The pin is carried in a collar 39 adjustably secured on the lever 38 so that it may be brought into proper relation to 100 the cam plates on the disk 36. The upper end of the lever is connected by a link 40 with an arm 41 secured to the outer end of a rock shaft 42. The rock shaft extends 105 above the rear ends of the levers 30 and 31, 110 and is provided with two oppositely projecting arms 43 and 44 which are arranged to engage and actuate said levers. The ratchet disk 36 is loosely mounted on a stud 45 which is conveniently screwed into the end of the 115 cam shaft 6. The disk is held from rotation by a spring pawl 46 arranged to engage the teeth which are formed on the periphery of the disk. The disk is actuated at proper intervals by a pawl 47 pivoted to an 120 arm 48 which is secured to the end of a rock shaft 49 which carries the oscillating segment 12. The pawl 47 is normally held up 125 out of engagement with the teeth on the disk 36 by a finger 50 which projects laterally 130

from a lever 51 and underlies the pawl. The lever 51 is pivoted on the stud which supports the controller lever 14 and is provided at its front end with a laterally projecting finger 52 which overlies the edge of the pattern chain. Certain links of the pattern chain are provided with lugs 53 arranged to engage the projecting finger 52 and lift the forward end of the lever 51. When one of these links is carried under the finger 51 by the forward feed of the pattern chain the lever 51 is rocked to allow the pawl 47 to engage the teeth on the disk 36, so that the disk is advanced a distance of one tooth during the reciprocation of the segment 12 and rock shaft 49.

When the parts are in the position indicated in the drawings, with the pin 37 resting against the outer side of one of the plates 34, the arm 44 is in a position to depress the rear end of the lever 31, and thus raise the yarn guide 22 so that the white yarn is held out of engagement with the needles. At this time the arm 43 is raised so that the rear end of the lever 30 is free to rise, and the yarn guide 21 is therefore held down by its spring 25 in position to feed the black yarn B to the needles. If the controller cam shaft is in the position indicated in Figs. 3 and 7, the rear end of the lever 29 is also free to rise, so that the yarn guide 20 for the reinforce yarn will be held down by its spring 25 in position to feed the reinforce yarn to the needles. When the yarn is to be changed a lug 53 on the pattern chain strikes the front end of the lever 51, thus allowing the actuating pawl 47 to advance the cam disk 36 a distance of one tooth. During this movement of the cam disk the pin 37 engages the front end of the plate 35 and is carried inward so that it rests against the inner edge of the plate 35. The movement thus imparted to the lever 38 rocks the rock shaft 42 in a direction to depress the arm 43 so that it depresses the rear end of the lever 30 and raises the yarn guide 21 to withdraw the black yarns B and b from the needles. The same movement of the rock shaft raises the arm 44 so that the rear end of the lever 31 is free to rise and the yarn guide 22 is moved down by its spring 25 to deliver the white yarn to the needles. The white yarn is now fed to the needles until the cam disk 36 is again moved, when the rock shaft 40 is again actuated to depress the lever 31 and release the lever 30, thus shifting the yarn guides to withdraw the white yarn and to present the black yarn to the needles. The front end of the yarn guide 20 projects in front of the end of the yarn guide 21, so that the guide 20 is raised to withdraw the reinforce yarn when the guide 21 is raised to withdraw the main black yarn. By properly arranging the lugs 53 on the pattern

chain the yarn may be changed from black to white, or white to black, at any point in the knitting of the stocking, and the change from one yarn to the other may be made as frequently as desired by proper arrangement of the lugs on the pattern chain. Any desired change in the operation of the yarn changing mechanism may be readily made by changing or shifting the links of the pattern chain which are provided with lugs 53, and the yarn changing mechanism may be actuated to produce stripes at any desired point in the stocking, or to change the yarn at any desired point during the knitting of either the heel or toe.

When a yarn is withdrawn from the needles by the upward movement of one of the yarn guides, the yarn which is thus withdrawn is held until it is again presented to the needles by a yarn holding device arranged within the needles of the needle cylinder. This yarn holding device comprises a plate 54 secured to the latch ring, and a co-operating clamping arm 55. The arm 55 is carried by a rock shaft 56 and is held in engagement with the plate 54 by a spring 57 which is connected to the free end of an arm 58 secured to the end of the rock shaft. An inclined finger 59 projects from the end of the arm 55 into position to direct the yarn under the arm as the needle cylinder revolves. In order to insure the passage of the yarn between the plate and arm 55 so that it will be securely clamped, the plate 54 is provided with an upwardly projecting finger 60 so arranged that the yarn will pass readily over it as the cylinder rotates in a forward direction or in the direction of the arrow, Fig. 4, but will pass under the projecting end of the finger when the cylinder rotates in a reverse direction. The plate is also preferably provided with a safety notch 61 which will catch the yarn as the cylinder rotates in a reverse direction in case the yarn should by any chance have passed over the retaining finger 60. This safety notch in such case will catch the yarn so that it will pass properly under the finger 59 and over the plate 54 during the next forward movement of the needle cylinder. The finger 60 and safety notch 61 thus act to insure the proper engagement of the yarn with the holding devices when the change of yarn is effected during the reciprocatory knitting. With these devices the lifting of the arm 55 to insure the passage of the yarn under it is not necessary, and the arm may remain continuously in engagement with the plate 54. This enables the spring takeups which act upon the yarns used during reciprocatory knitting to maintain a constant light tension upon the yarns, and avoids the necessity of providing devices for throwing the takeups out of action.

While it is preferred to employ the con-

struction and arrangement of parts shown and described, especially in embodying the invention in a Banner machine, since this construction and arrangement can readily be embodied in existing machines without change or reorganization of the parts, it will be understood that this construction and arrangement is not essential to the broader features of the invention, and may be varied and modified to suit the requirements of the machine in which the invention is to be embodied.

Having explained the nature and object of the invention, and specifically described one form of machine in which it may be embodied, what I claim is:

1. A circular knitting machine, having, in combination, a rotary needle cylinder, needle actuating cams, controller cams for controlling the action of the needle actuating cams on the needle, yarn guides, a cam movable independently of the controller cams, connections between the cam and yarn guides, a ratchet connected with the cam, an actuating pawl for the ratchet, mechanism for actuating the controller cams, a pattern chain, and means for independently controlling the actuating mechanism and actuating pawl from the pattern chain, substantially as described.

2. A circular knitting machine, having, in combination, a rotary needle cylinder, needle actuating cams, a cam shaft carrying cams for controlling the action of the needle actuating cams on the needles, vertically movable yarn guides, levers engaging the guides, actuating levers connected with the guide engaging levers, a rock shaft provided with arms arranged to alternately operate the actuating levers, a cam connected to actuate the rock shaft, mechanism for actuating the controller cam shaft, mechanism for independently actuating the yarn guide cam, and a pattern chain for controlling the actuating mechanisms, substantially as described.

3. A circular knitting machine, having, in combination, knitting cylinders, cams and connections for controlling the knitting, mechanism for actuating the controller cams, a pattern chain for controlling the actuating mechanism, yarn changing devices, a cam movable independently of the controller cams for actuating the yarn changing devices to change the yarn, and mechanism in-

dependently controlled from the pattern chain for actuating the yarn changing cams, substantially as described.

4. A circular knitting machine, having, in combination, a rotary needle cylinder, needle actuating cams, a cam shaft carrying cams for controlling the action of the needle actuating cams on the needles, vertically movable yarn guides, a cam and connections for raising and lowering the guides, actuating mechanism for the cam shaft, actuating mechanism for the yarn guide cam, a pattern chain, and means for independently controlling the actuating mechanisms from the pattern chain, substantially as described.

5. A circular knitting machine, having, in combination, a needle cylinder, needle actuating cams, mechanism for relatively rotating and reciprocating the needle cylinder and cams, a cam shaft carrying cams for controlling the action of the needle actuating cams on the needles, vertically movable yarn guides, levers engaging the guides, actuating levers connected with the guide engaging levers, a rock shaft provided with arms arranged to alternately engage and depress the actuating levers, a cam connected to actuate the rock shaft, and devices for intermittently actuating the cam, substantially as described.

6. A circular knitting machine, having, in combination, a needle cylinder, a series of vertically movable yarn guides, a yarn holding arm within the needles, a coöperating yarn supporting plate, and a yarn retaining finger on the plate beyond the knitting point arranged to direct the yarn under the plate on the reverse stroke of the needle cylinder, substantially as described.

7. A circular knitting machine, having, in combination, a needle cylinder, a series of vertically movable yarn guides, a yarn holding arm 55 having a yarn deflecting finger 59, and a plate 54 provided with a projecting finger 60, substantially as described.

8. A circular knitting machine, having, in combination, a needle cylinder, a series of vertically movable yarn guides, a yarn holding arm 55 having a yarn deflecting finger 59, and a plate 54 provided with a projecting finger 60 and with a notch 61, substantially as described.
